CLAIM

The ornamental design for a arc resonant cavity acoustic foam as shown and described.

DESCRIPTION

FIG. 1 is a bottom, front perspective view of a arc resonant cavity acoustic foam showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top, rear perspective view thereof.
